UNITED STATES PATENT OFFICE

2,513,029

BOTTLEHOLDER

Lou Lapointe, Toronto, Ontario, Canada

Application January 8, 1949; Serial No. 69,889

3. Claims. (Cl. 248—311)

1

My invention relates to improvements in holding devices for detachably supporting a bottle on a wall for convenience in dispensing fluid contents from the bottle from time to time as occasion demands.

More particularly the invention appertains to a holder for a commercial bottle of protamine zinc insulin which is commonly used in filling a hypodermic syringe for a diabetic person required to take the approved insulin treatment. It is customary for a diabetic person to carry out the injection treatments and in doing so the required dosage must be introduced into the hypodermic syringe for each treatment. The filling of the syringe is an awkward and difficult operation since it requires that the bottle be invertedly held in one hand while the other hand is used to hold the syringe and to force the needle thereof through the rubber cap on the bottle in order to abstract the insulin material. The bottle and the syringe must be held very steady in order to avoid bending or breaking the needle.

Hence it is the aim of the present invention to provide a holding device for supporting the bottle on a wall so as to leave the hands free to manipulate the syringe in order to facilitate the filling operation and to avoid breaking of the needle.

A further object is to provide a holder comprising a bracket and a bottle case detachably connected by a tapered lug fitted in an apertured element by which the bottle is supported in an inverted position for the charging of a hypodermic syringe. The apertured element provides a tapered hole in the bracket in which the tapered lug fits with binding engagement to hold the case firmly suspended. The tapered lug projects from a side of the case and an advantage of the construction is that in grasping the case to remove it after the syringe has been filled, the case affords purchase for forcing the tapered lug out of the hole.

A further object is to supply an ejector device for facilitating the detachment of the case from the bracket. The ejector device takes the form of a cam lever on the bracket by which leverage on a cam face is obtained to force the tapered pin out of the hole. This provides a convenient arrangement which requires little effort on the part of the user.

Another feature of the invention is that the case is made up of a cylindrical body having a screw cap at each end, one for engaging the base of the bottle and the other for engaging the closure thereof. The screw cap which engages

2

the base of the bottle is fitted with a gasket of cork or like material and secures the bottle in said body by clamping it against a shoulder portion at the other end through which the neck of the bottle protrudes. The other screw cap is lined with a layer or wad of absorbent cotton held in place by a ring and wetted with alcohol to sterilize the closure of the bottle.

The invention produces a serviceable and convenient holder which enables the bottle to be retained in the case until it is empty, and one which permits the bottle to be removed from the bracket along with the case after the filling of a syringe and then stored in a refrigerator until again required.

The accompanying drawing illustrates the preferred embodiment of the invention, in which:

Fig. 1 is a sectionalized elevation of the holder showing a bottle therein.

Fig. 2 is a sectional view of the case with the bottle therein.

Fig. 3 is a cross section taken on line 3—3 of Fig. 1.

Fig. 4 is a front view of Fig. 1.

Fig. 5 is a detail of a split ring which forms a part of the retaining means for the absorbent cotton.

Fig. 6 is a detail of a keeper ring which forms the other part of the retaining means for the absorbent cotton.

In the drawing the reference numeral 1 denotes the case as a whole, which case comprises a cylindrical body 2 receptive to a standard bottle 3 in which insulin is sealed as by a permanent closure 4 including a rubber disc 5 suited to be pierced by the needle 6, Fig. 1, of a hypodermic syringe used for treatment of diabetes.

The body 2 is open through its length and one end is reduced to provide a shoulder 7 against which the top end of the bottle is seated adjacent to its neck portion. The neck of the bottle protrudes from said body. The bottle is clamped against said shoulder by a screw cap 8 fitted on the opposite end of said body. Said screw cap is lined with a disc of cork or comparable material 9 to preclude damage to the bottle.

The exposed top end of the bottle is enclosed by a screw cap 10. This cap is fitted with a layer or wad of absorbent cotton which is impregnated with a suitable sterilizing agent, such as alcohol. The absorbent cotton contacts the closure 4 and is held in the cap 10 by means of a keeper ring 11 and a split retaining ring 12, the latter being seated in a groove 13. The cap 10 is unscrewed from the body 2 when the bottle is to be used,

which body may be supplied with a slot 14 forming a sight by which the level of the contents of the bottle may be seen. A tapered lug 15 is integrally formed on a side of the body 2 to project outwardly thereof. The lug constitutes a part of the interfitting connection by which the case is detachably secured to the bracket.

The bracket is generally denoted at 16 and is desirably a truncated conical member of a hollow construction formed by a chamber 17 open to the wide or base end 18. A pierced flange 19 is provided on said base end to enable the bracket to be permanently attached to a wall 20, Fig. 1, as by screws or like fastening elements.

The wall portion 21 at the small end of the bracket is provided with a central tapered hole 22 which conforms to the taper of the lug 15 and is open to the chamber 17. A cam lever 23 is loosely fitted in a longitudinal slot 24 in a side wall of the bracket and fulcrumed on a pin 25. The cam lever is bent inwardly at its fulcrum to extend across the inner end of the tapered hole 22 and the vent end is fashioned with a cam face 26 for engaging the lug to force it out of the hole when the lever is pressed inwardly. The cam lever is preferably located at the under side of the bracket so that it will swing outwardly by gravity action. A stop piece 27 is formed on the distal end of the cam lever to engage an adjacent wall portion of the bracket in order to limit outward movement of the cam lever.

For convenience in using the insulin the bracket may be fastened on the wall of a bathroom. The bottle is retained in the case so that it may be kept in a refrigerator when not in use. When it is required that the hypodermic syringe be charged for a treatment the case containing the bottle is removed from the refrigerator and the cap 19 is detached. The case is then attached to the bracket in an inverted position by inserting the lug in the tapered hole and pressing it into firm binding engagement. Whereupon the syringe can conveniently be filled as required by using the bracket as a rest for the hands to steady the needle in piercing the rubber of the bottle closure. The operation can be carried out quickly without the likelihood of damaging the needle. On filling the syringe the case can be easily detached from the bracket by pressing the cam lever inwardly to cause the cam face thereof to disengage the lug. The case with the bottle therein can then be put back in the refrigerator until again required.

What I claim is:

1. A holder of the class described comprising a wall bracket having an outwardly protruding wall portion terminating in an end face and provided with an opening therethrough which is inwardly tapered, a bottle-enclosing case, a tapered lug on a side of said case conforming to said opening for wedging engagement therein with its small end projecting from the remote side of said wall portion with respect to said end face, and a cam lever pivoted on said bracket and having a cam face disposed to swing toward said remote side to engage the small end of said lug so that said cam lever is operative to free said lug of its wedging engagement.

2. A holder of the class described comprising a chambered bracket of a truncated conical shape, of which the large end forms a base portion for attachment to a wall surface, the small end of said bracket having a wall section which is centrally pierced to provide an inwardly tapered hole open to the chamber, a longitudinal slot provided in a side of said bracket, a cam lever disposed lengthwise of said slot and having an end which is bent to extend inwardly of said chamber adjacent to the inner side of said wall section, said lever being pivoted on said bracket at its bent end, said bent end having a cam face adjacent to said hole, and a case having a tapered lug thereon for detachably engaging in said hole and protruding inwardly of said wall section whereby said lever can be actuated to engage said lug to force it outwardly of said hole.

3. A holder as set forth in claim 2, in which the slot is arranged at the under side of said bracket so that the distal end of the cam lever will tend to swing downwardly under the influence of gravity.

LOU LAPOINTE.
